BERNARD F. STENZ, OF NEW YORK, N. Y., ASSIGNOR TO SIMPLEX LITHOGRAPH COMPANY, OF NEW YORK, N. Y., A CORPORATION OF NEW YORK.

SAMPLE-CARD.

1,236,118.

Specification of Letters Patent.

Patented Aug. 7, 1917.

Application filed September 14, 1916. Serial No. 120,047.

To all whom it may concern:

Be it known that I, BERNARD F. STENZ, a citizen of the United States, and resident of New York city, borough of Manhattan, in 5 the county of New York and State of New York, have invented a new and Improved Sample-Card, of which the following is a full, clear, and exact description.

The present invention relates to sample 10 cards adapted for use in the piece-goods art, and to display samples or replicas of samples of woven textile material such as ginghams, percales, silks and ribbons.

The object of the present invention is to 15 produce a sample card in which the sample surface shall be protected by an integrally formed raised guard surface.

A further object is to produce a sample 20 card in which the effect is produced of a sample displayed beneath an apertured mat and showing through the aperture while in fact the body portion and the panel in which the sample is displayed are all formed integrally.

25 A further object of the invention is to produce a sample card provided with integrally formed depressed sample panels, the said panels having a sample surface within such recess below the surface of the body

30 portion representing an embossed replica of a sample of textile fabric.

To the above ends, my invention consists 35 of a sample card in which the body portion and a sample panel are formed integrally, having a guard raised above the sample panel and protecting the sample surface of such panel, and it further consists of a sample card having a body portion and a sample panel depressed below the surface of the 40 body portion and provided with a sample surface in a plane parallel to the surface of the body portion, such sample surface having an embossed replica of a sample of textile fabric.

45 My invention further consists of the sample card which will be hereinafter described and claimed.

A sample card embodying my invention is shown in the accompanying drawings, in 50 which—

Figure 1 shows a front elevation of my improved sample card embodying a plurality of symmetrically arranged rectangular sample panels;

Fig. 2 is a vertical section taken on the 55 line 2—2 in Fig. 1;

Fig. 3 is a modified form in which the sample panels are elliptical in shape;

Fig. 4 shows a modified form in which the sample panels are in the plane of the body 60 portion but provided with an embossed marginal protecting guard extending beyond the front surface; and.

Fig. 5 shows a vertical section taken on the line 5—5 in Fig. 4. 65

It has been customary in manufacturing sample cards to provide a suitable backing upon which actual samples of textile materials are adhesively secured, and to cover the backing with a front piece or mat provided with apertures which when laid over the samples of textile material cover the raw edges of the material, showing the samples through the apertures. Such cards are expensive to manufacture, however, owing 70 to the fact that the cutting up of the materials and the assembling is an expensive operation, not only for the labor, but for the actual materials, and one of the objects of my invention as heretofore stated is to imitate a sample card, so formed, by the use 75 of a single piece of material only and without the use of actual textile samples. 80

As shown in Fig. 1, the improved sample card consists of a body portion 1, which is 85 provided with a sample panel 2, there being in the illustrated embodiment ten of such sample panels, each of which has a sample surface displaying a replica of textile fabric different from all the others. 90

The sample panels 2 are formed integrally with the body portion 1 by embossing dies and as shown in Figs. 1 and 2 they are depressed below the surface of the body portion 1, there being formed a distinct marginal edge 3 about the recess or panel. Preferably the front surface of the panels 2 will be in a plane parallel to the front face of the body portion 1, and this surface, which I designate the sample surface of the 100 panel, will be embossed to represent a sample of textile fabric as at 5, showing different patterns. As shown in Fig. 3, the panels may be elliptical in form.

The completed sample card will have the 105 effect of samples of actual fabric adhesively secured to a back piece and covered by a mat provided with openings, but as the

whole is formed of one integral piece of material preferably cardboard suitable for the purpose, there will be a considerable saving as compared with the old style of sample card.

It is to be noted that by forming the sample surface of the panel below the body portion of the card it will be protected from rubbing and the printed and embossed samples will not become marred and obliterated.

In Figs. 4 and 5 practically the same result is accomplished as in the form described. In this form of the device the sample panels 6 are formed by embossing and printing, but they are in the same plane as the body portion 7, and a marginal bead or rib 8 is embossed above the surface of the body portion 7 on one side which provides a well defined edge 9 surrounding the panel, and at the same time affords protection for the sample surface of the panel.

Having thus described my invention, I claim as new and desire to secure by Letters Patent:

A sample card comprising a body and a sample panel formed integrally, said panel having a sample surface representing a sample of textile material, the body portion, sample panel and sample surface being formed by embossing and the sample surface of the panel being below the upper surface of the body portion and the body portion struck up forming a raised guard for the embossed sample surface of the sample panel.

In testimony whereof I have signed my name to the specification in the presence of two subscribing witnesses.

BERNARD F. STENZ.
